UNITED STATES PATENT OFFICE.

GEORGE PEEBLES, OF ELIZABETH, NEW JERSEY, ASSIGNOR TO SELBEC, INC., OF NEW YORK, N. Y., A CORPORATION OF NEW YORK.

ROLLER VACUUM EXTRACTOR.

Application filed September 23, 1925. Serial No. 58,119.

The invention relates to a class of vacuum boxes used for extracting water, with which a fabric is saturated, in the process of making textiles and paper.

- 5 The present invention has particular reference to a roller vacuum extractor unit, which, especially when used in drying of textiles, gives a uniformity of extraction that is impossible to obtain at the present 10 time by the well-known centrifugal method. The use of rollers in the process of paper manufacture is particularly desirable because it insures longer life for the felt or wire, avoids rips and tears and extracts the 15 water from the paper while allowing a lower steam pressure to be maintained in the calender rolls.

The principal object of the invention is to provide a vacuum box of this character 20 which is applicable to varying widths of machines and I accomplish this object by an arrangement of a shield whereby it is possible to accommodate almost any width desired.

- 25 A further purpose of this invention is the provision of certain novel features of arrangement and construction of parts, comprising rolls, suction box and plugs, which form three sides of a closed box, the fourth 30 side being formed by a travelling belt, whereby suction applied to the box, must of necessity extract water from the paper stock through the felt belt and be drawn away through the piping to the suction 35 pump.

The invention is illustratively exemplified in the accompanying drawings, in which Figure 1 is a perspective view of a paper-making machine equipped with my 40 improved type of roller vacuum extractor; Figure 2 is a plan view of the roller vacuum extractor; Figure 3 is a plan view on an enlarged scale of one end of the device and Figure 4 is a substantially longitudinal sectional view through a roller and associated parts of the box; Figure 5 is a substantially 45 longitudinal sectional view of the suction box and taken on a center line of the device; Figure 6 is a substantially transverse sectional view taken on lines 6-6 of Figure 5; Figure 7 is a transverse sectional view taken on lines 7-7 of Figure 5; Figure 8 is an end view of the roller vacuum extractor; Figure 9 is a transverse sectional view 55 taken on lines 9-9 of Figure 5 and Figure

10 is a transverse sectional view taken on lines 10-10 of Figure 5.

Referring to the drawings, 10 denotes the standards of a cylinder machine, which is illustrated to show my improved roller vacuum extractor embodied therein, but it will be clear to those skilled in the art that the installation is applicable equally well to wet machines used in the manufacture of cotton or woolen goods, and which is provided with the usual number of rollers 11 supported on the standards and adapted to carry the cloth fabric 12 in the well-known manner.

At a suitable station in the machine and carried at its ends on the standards 10, is disposed the roller vacuum extractor, which comprises a trough-shaped box 13, having a transverse section substantially as illustrated in Figure 10. Each end of the box 13 is provided with an extension 14 for accommodating the end bearings 15 of the main rollers 16 and at each end of the longitudinal center line of the box the latter is provided with an integral upstanding web 17, 70 a portion thereof being disposed between the rollers 16 and having its surfaces machined where contact with the rollers is made. The top surface of the web 17 is also machined on an elevation corresponding 75 substantially with longitudinal center line of the rollers 16. The box 13 is tapped to receive a pipe connection 18 with a vacuum pump, not shown.

The main rollers 16 are disposed on the 80 same elevation and operate parallel to one another. They are constructed preferably of brass pipe, machined to a true surface. The ends of each pipe are provided with extension pieces 19 brazed in the brass and 85 having suitably turned ends 20 which accommodate annular ball bearings 21 and which terminate in short shafts 22 and carry spur gears 23. The gears 23 are keyed to the shafts 22. The ball bearings 21 are of the usual type having inner and outer rings 24 and intermediate balls 25, the outer rings being bolted to the ends of the suction box 13 and protected by suitable covers or caps 26 which embrace the shafts 22 and screw 105 into the openings in the box. The casing 27 forming part of the suction box 13 carries on the vertical center line a stud shaft 28 secured in position by a set screw 29 and having a spur gear 30 and sprocket 31 rotat- 110

ably mounted on its outer end. The spur gear 30 is driven by the sprocket and is in mesh with each of the other gears 23. It is intended to provide a set of gears for each 5 end of the device, but only one drive sprocket is needed and may be driven by a chain operated by a sprocket carried on any shaft, not shown, but located at a convenient place in the paper machine, the rate of speed 10 of rotation of the sprockets being such as to give the same surface speed to the rollers as that maintained by the belt. Located at spaced intervals throughout the length of the rollers 16 and arranged there between are 15 spacing rollers 31^a mounted in the ends of upright rods 3 which are screwed at their lower ends into bosses projecting upwardly from the bottom wall of the box, the purpose of the spacing rollers 31 being to support 20 the main rollers and prevent deflection thereof towards each other, a phenomenon due to unbalanced forces (atmospheric pressure on the outer half circumference of the rollers and vacuum of approximately 15 25 inches on the inner half circumference).

Embracing one quarter of the upper circumferences of adjacent rollers 16 and disposed at opposite ends thereof are adjusting plugs 33 comprising T-shaped members the 30 under surfaces of the lateral arms being machined to fit closely the curved surfaces of the rollers. The upper or outer surface of each plug 33 is provided with a sheet metal shield 34 which extends transversely 35 of the plug a short distance beyond the edges of the latter, these projecting portions of the shield 34 being for the purpose of presenting a curved entering surface for the overlapping edges of the belt. The steam 40 portions of the plugs 33 rest upon the upper face of the webs 17 projecting upright from the bottom of the suction box 13. The depending stem of the plug 33 is provided with a plurality of aligned openings or 45 boxes 35 through which a pin 36 may be inserted, the latter being disposed to bear against the outer surface of two relatively small lugs 37 cast as a part of the bearing casing 27. The purpose of the lugs 37 is 50 to prevent the plug 33 from being drawn inward by the action of the suction in the box. Various widths of paper stock may be accommodated by adjusting the pin 36 to any one of boxes 35. Preferably the inner edge 55 of the pin 36 is set so as to just underlap the edges of the paper stock.

Arranged on each side of the suction box 13 and held in contact with both the latter and the under side of a main roller 13 are 60 strips 38 of hard rubber, preferably rectangular in transverse section and of a length substantially that of the rollers themselves. The strips 38 form side seals for the vacuum space and are backed by metal strips 39 having V-shaped grooves running longitudinally 65

thereof and fitting the corners of the rubber seals 38, as illustrated clearly in Figure 9. The metal strips 39 are adjusted towards the rubber seals 38 by means of screws 40 disposed in uniform spaced relation with respect to each other, each screw being carried by an inclined flange or extension 41 on the outside of each upright wall of the suction box 13. Each screw 40 is further provided with a lock nut 42 adjustable over the screw 75 and against the flange 41 to lock the screw itself in adjusted position.

A complete seal between the rollers and box is effected by the provision of end seals 80 each of which comprises a curved rubber member 43 of substantial thickness having one edge beveled, as illustrated in Figure 4, to fit a correspondingly beveled or counter-sunk end wall of the suction box. The seals of which there are two sets at an end 85 are shaped to embrace the inner half circumference of the main rollers 16 and abut at their one end against the side seals 38 and at their other end against the under side of the adjustable plug 33 and shield 34. The 90 lower quarter end seals 43 are retained and pressed into place by a follower 44, which is triangularly shaped and provided with a curved recess on two sides to receive the end of the seals 43, and which carries a 95 screw bolt 45 adjustable in a threaded opening 46 in the center vertical web 17 of the suction box. The upper quarters of the seals 43 are pressed into contact with the periphery of the roller by the shield itself. 100

In Figures 1 and 10, a travelling felt belt 47 is illustrated supported on the main rollers 16 and forming between the latter one wall of the suction chamber. The other walls as described, comprise the suction box 105 itself and plugs. Therefore any vacuum maintained in the space between felt and other walls will of necessity draw any water from the paper stock 48, resting on the felt belt through the latter and conduct the 110 water through suitable pipe connection to a suction pump.

Having now described the nature of my invention what I claim and desire to secure by Letters Patent is:

1. In a machine for extracting liquid from saturated fabric, in combination, a vacuum box having side and end walls, spaced rollers journaled in said end walls and each thereof having its upper surface tangent with the fabric sealing means arranged between each side wall and the adjacent surface of a roller comprising a strip of rectangular compressible section sealing material, a backing strip for the sealing material and adjustable means carried by the side walls of the box and engaged with the backing to hold the sealing material in contact with both the surfaces of the roller and side wall. 120
2. In a machine for extracting liquid from 125

- saturated fabric carrying paper stock, in combination, a vacuum box having side and end walls spaced rollers journalled in said end walls, each roller having its upper surface tangent with the fabric, plugs adjustably supported at opposite ends of the box and arranged with respect to the rollers to accommodate varying widths of paper stock, compressible sealing means for the ends and 5 faces of the rollers and box, and screw adjustments for supporting and urging the side sealing means against the roller and box, whereby vacuum in the box will tend to draw the liquid from the fabric into the 10 box.
3. In a machine for extracting liquid from saturated fabric carrying paper stock in combination, a vacuum box having side and end walls and an upstanding longitudinally 15 disposed center web at opposite ends of the box, spaced rollers journalled in said end walls, each roller having its upper surface tangent with the fabric, adjustable plugs supported on the said webs and having a 20 portion of their surfaces closely embracing the upper surfaces of the rollers, compressible means for sealing the spaces between the rollers and box, and screw adjustments for supporting and urging the side sealing 25 means against the roller and box, whereby vacuum in the latter will tend to draw the liquid from the fabric into the box.
4. In a machine for extracting liquid from saturated fabric in the manufacture of paper 30 and the like, in combination, a vacuum box having side and end walls and an upstanding longitudinally disposed center web at each end, spaced rollers journalled in said end walls and having their upper surfaces 35 tangent with the said fabric, the lower surfaces of the rollers being spaced above the upper ends of the side walls of the box, adjustable plugs supported on the webs and having oppositely extending portion closely 40 embracing the upper surfaces of the rollers, a shield for each plug comprising a metal member arranged on the plug and extending beyond the latter at each side and curved to embrace closely the surface of the rollers 45 beyond the plug, adjustable compressible sealing means between the rollers and the adjacent side walls, and screw adjustments for supporting and urging the side sealing means against the roller and box, whereby 50 vacuum in the box will tend to draw the liquid from the fabric into the box.
5. In a vacuum box, the combination with a trough-shaped member having side and end walls of rollers journalled in the end walls and arranged over the side walls, a 55 plug and shield for opposite ends of the box, means for adjusting plugs with respect to the ends of the rollers, compressible means for sealing the space between the 60 rollers and side walls, and screw adjustments for supporting and urging the side sealing means against the roller and box, and compressible means for sealing the spaces between the ends of the rollers and walls.
6. In a vacuum box, the combination with 70 a trough-shaped receptacle having side walls, end walls and a center web adjacent each end of spaced rollers journalled in said end walls, plugs between the rollers at opposite ends, and means for adjusting the plugs longitudinally of the rollers, comprising a removably insertable member for a series of spaced openings in the plug, said member being adapted to bear against a portion of the end wall to prevent the plug being 75 drawn inwardly by the vacuum in the box.
7. In a machine for extracting liquid from saturated fabric, in combination, a vacuum box having side and end walls and a center 80 web adjacent each end, a pair of spaced rollers journalled in the end walls and having their lower surfaces arranged just above the side walls, and adjustable plugs arranged on each web and having a shield embracing the upper surfaces of the rollers, sealing strips for the spaces between the rollers and side walls, backing pieces for the strips, adjustable screws carried by the box and adapted to engage the backing strips and cause the sealing strips to press close the 85 space between the wall and roller, and resilient end seals embracing the surfaces of the rollers overlying the interior of the vacuum box, and means for packing the end seals against a portion of the end walls 90 and rollers.
8. In a machine for extracting liquid from saturated fabric, in combination, a vacuum box comprising a base plate with upstanding side and end walls, the side walls at 95 opposite ends being closed by a bridge portion provided with a center longitudinal web, rollers journalled in the end walls and spaced apart to bring the lower surfaces short of the upper ends of the side walls, adjustable plugs arranged on the webs and provided with oppositely projecting portions to closely embrace the upper surfaces of the rollers, sealing means between the ends of the rollers and end walls, sealing means 100 between the side walls and rollers comprising strips of sealing material disposed against the side walls and means for adjusting the material upwardly along the side walls on the vertical center lines of 105 the rollers to seal the spaces between the 110 rollers and the side walls.
9. In a machine for extracting liquid from saturated fabric, in combination, a vacuum box having side and end walls, spaced rollers 115 journalled in said end walls, adjustable sealing means between the rollers and the walls, and means arranged between the rollers to prevent the latter from deflecting towards 120 each other.

10. In a vacuum box of the character described the combination of spaced rollers journalled in said box, a resilient seal to embrace the top, inner surfaces of the rollers 5 within the box, and a triangular follower adjustable toward each end of the box and against the seal to close the space between the roller and box.

11. In a machine for extracting liquid 10 from saturated fabric, in combination, a vacuum box, having side and end walls and extensions to receive bearings, the space between side and end walls being closed by a bridge portion projecting inwardly from 15 the end, the bridge portion having an up-

standing longitudinal central web, rollers rotatably mounted in bearings in the said extensions, adjustable plugs for the rollers having perforated projections projecting through openings in the extensions, pins 20 insertable in said perforations to engage the extensions and fix the positions of the plugs, shields for the plugs having their sides curved to closely embrace the surfaces of the rollers beyond the plugs, and side and end seals adjustable into contact with the rollers and side and end walls.

In testimony whereof he has affixed his signature.

GEORGE PEEBLES.
